United States Patent Office

GEORGE LAWTON, OF TRENTON, NEW JERSEY, ASSIGNOR TO GEORGE JAMES, OF SAME PLACE.

Letters Patent No. 65,244, dated May 28, 1867.

IMPROVED MACHINE FOR STAMPING CLAY DOOR-KNOBS.

The Schedule referred to in these Letters Patent and making part of the same.

TO ALL WHOM IT MAY CONCERN:

Be it known that I, GEORGE LAWTON, of Trenton, in the county of Mercer, and State of New Jersey, have invented a new and improved Machine for Stamping Clay Door-Knobs, &c.; and I do hereby declare that the following is a full, clear, and exact description thereof, which will enable others skilled in the art to make and use the same, reference being had to the accompanying drawings forming part of this specification, in which—

Figure 1, sheet 1, is a front elevation of my improved machine.

Figure 2, sheet 2, is a vertical cross-section of the same, taken on the line $x x$, fig. 1.

Similar letters of reference indicate like parts.

The object of this invention is to construct a machine whereby door-knobs and other articles of clay may be formed or stamped in the most simple and efficient manner, completing the door-knobs or other articles as far as the working in clay is concerned.

The invention consists in such an arrangement of the machine that the stamping process may be perfect, the upper die falling down three times with variable force, so as to completely finish the article. The machine is also so arranged as to prepare the holes in the knobs, or other articles, for the reception of the shanks of said knobs or other articles, said holes branching towards the sides for the purpose of making the lead filling adhere.

A represents the frame of the machine, consisting of upright posts and horizontal timbers and braces, and is made of wood or any other suitable material. Suitable boxes are arranged on the frame, and the horizontal shaft B is mounted thereon and receives rotary motion from a pinion, a, on the driving-shaft C, said pinion meshing into a gear-wheel, b, on the shaft B, as is shown in the drawings. To the shaft B are secured two or more sets of cams D, which are so arranged as to operate the dies alternately. Beds E are arranged on the front side of the frame A, upon which beds the lower dies or matrices c are arranged and held by means of set-screws d, so that they may be removed and easily replaced. The upper dies e are secured to the hammers F, which are attached to the lower end of vertical sliding-shafts G, each of the latter being provided with an arm, f, which is operated by the cams D on the shaft B. The ends of the hammers are grooved and fit over tongues g, which are arranged on the upright of the frame A, as shown in fig. 1, so that thereby the hammers are well guided.

For each set of cams D on the shaft B is provided a shaft, G. To each of the latter is secured a hammer, F, and each of these may hold two (more or less) upper dies e, the latter corresponding with the number of and being exactly above the matrices c on the beds E. The upper dies are removable from the hammer, as the matrices may be detached from the beds.

By the revolution of the shaft B, the cam D comes in contact with the arm f, and thereby raises the shaft G. The matrices are then filled with clay, the shaft G is then released from the cam, and the hammer falls upon the bed E, the upper dies and matrices coming together, and between them forming the clay into the required shape.

Each set or series of cams D consists of three parts. The first part, h, raises the hammer and dies e up, so that the upper surface of the hammer comes almost in contact with the upper timbers of the frame A. The second part, i, raises the hammer half as high as h; and the third part, k, raises the same half as high as i. By the action of the cam h the hammer falls the greatest distance, which is reduced to half by the cam i, and again subdivided by the action of cam k. The cam h has a surface of sufficient extension to retain the hammer in its elevated position long enough to allow the removal of the finished knobs from and the insertion of clay for new ones into the matrices. The different motions of the upper dies are required to give to the article the required and necessary finish.

To facilitate the removal from the matrices of the ready-stamped knobs or other articles, I have arranged the pushers H, which are tubes, closed at the top, extending through the matrices and beds E downward, and connected at their lower ends with each other (those arranged in the same bed) by a horizontal connecting-rod, l. The same is secured to the lower end of an upright rod, m, the upper end of which is pivoted to an elbow-lever, n, which is pivoted at its angle to the frame A. From the side of the cam h projects a side-cam, o, which pushes once during every revolution of the shaft B, and at the moment when the upper dies are being raised by the cam h against the vertical arm of the lever n, thereby raising the end of the horizontal arm of the same, and

also the rod *m*, bar *l*, and pushers *H*, thus lifting the article out of the matrices and facilitating their removal. As soon as the action of the cam *o* on the lever *n* ceases, the pushers are depressed again by means of a spring, *s*, which is fixed to the frame *A*, and acts upon pins or other projections on the bar *l*.

The pushers are provided with a shoulder, as shown in fig. 2, which forms part of the bottom of the matrices, while the part projecting above the shoulders forms the holes in the knobs for the reception of the shanks of said knobs, which said shanks are leaded into the knobs in the usual way.

The tubular pushers *H* work upon vertical rods *p*, which are attached to horizontal timbers below the beds *E*. To the inside of the pushers *H*, near their upper ends, are secured three (more or less) springs *q*, fig. 3, which operate horizontal pins *r*, which pins pass through holes in the tubes *H*. The small horizontal holes at the bottom of the main shank-hole of the knobs are made by means of these pins *r*, which are either attached to or form part of the springs *q*, as shown in fig. 2. The springs *q* and pins *r*, which are secured to the inside of the sliding-tubes *H*, are operated by the stationary rods or pins *p*, the upper ends of which are made in the shape of frusta of pyramids, as shown in fig. 2.

When the knobs are being stamped, the pushers *H*, springs *q*, and pins *r* are in position shown by dotted lines on the right-hand side matrices in fig. 1, that is, the pushers are down, and the springs are pushed out by the pins *p*, thus making the pins *r* project from the tubes *H*, so that by means of these pins the small horizontal holes at the bottom of the shank-holes of the knobs are formed. But as soon as the pushers *H* are elevated by the action of the cams *o*, levers *n*, rods *m*, and bars *l*, the springs *q* are freed from the pin *p* and draw the pins *r* into the tube *H*, (as shown in figs. 1 and 2,) thus permitting the removal of the knobs from the matrices. As soon as the pushers are depressed again by means of the spring *s*, the pin *p* comes in contact with the springs *q* again, and the pins *r* are thus made to project again from the sides of the pushers.

When articles are to be stamped which do not require to have holes formed in them, the pushers *H* may be replaced by others more simple in construction, whose office will be simply to lift the stamped articles out of the matrices so that they may be removed from the machine.

The forming of the horizontal holes at the bottom of the shank-holes in knobs, was heretofore very difficult, having to be done by means of drills. By my machine this portion of the work is greatly simplified. By means of the threefold action of the cams upon the upper dies the stamping of the articles in the matrices is greatly perfected, a much superior article being made thereby than by the machines now in general use.

What I claim as new, and desire to secure by Letters Patent, is—

1. The arrangement and construction of the cams *D*, whereby the dies *e* are operated three times in succession, the said cams consisting of the parts *h*, *i*, and *k*, all made and operating substantially as and for the purpose herein shown and described.
2. The device for raising the pushers *H* so as to lift the stamped articles out of the matrices *c*, the said device consisting of the cams *o*, levers *n*, and rods *m*, all made and operating substantially as herein shown and described.
3. The spring *s*, when arranged as herein shown and described, for the purpose of depressing the pushers *H* as set forth.
4. The device for forming the small horizontal holes at the bottom of the shank-holes in door-knobs, said device consisting of the pins *p*, tubes *H*, springs *q*, and pins *r*, all made and operating substantially as herein shown and described.
